DESIGN FOR AN ADJUSTABLE ONE PIECE JUNGLE BOOT

James A. Crotty, New York, N. Y.

Application September 14, 1943, Serial No. 111,124

Term of patent 7 years

(CL. D7—4)

To all whom it may concern:

Be it known that I, James A. Crotty, a citizen of the United States of America, residing in city of New York, county of New York, and State of New York, have invented a new, original, and ornamental Design for an Adjustable One Piece Jungle Boot, of which the following is a specification, reference being had to the accompanying drawing, forming part thereof.

Fig. 1 is a side elevational view of an adjustable one piece jungle boot showing my new design.

Fig. 2 is a perspective of the adjustable one piece jungle boot as shown in Figure 1, with the straps in open position.

The opposite side of the adjustable one piece jungle boot is conventional.

I claim:

The ornamental design for an adjustable one piece jungle boot, substantially as shown and described.

JAMES A. CROTTY.
